UNITED STATES PATENT OFFICE.

JAMES H. AUBLE, OF CINCINNATI, OHIO.

EXPANSIBLE AND CONTRACTIBLE TOOL.

1,332,455.

Specification of Letters Patent.

Patented Mar. 2, 1920.

Application filed April 14, 1917. Serial No. 161,973.

To all whom it may concern:

Be it known that I, JAMES H. AUBLE, a citizen of the United States, and a resident of the city of Cincinnati, in the county of 5 Hamilton and State of Ohio, have invented certain new and useful Improvements in Expansible and Contractible Tools, of which the following is a full, clear, and exact description, reference being had to the accompanying drawings, forming part of this 10 specification.

My invention relates to expansible and contractible tools such as reamers, taps, dies, lathe mandrels, bearings and the like which 15 are formed so that the tool can be expanded or contracted for different sizes of work. The object of the invention is to produce a machine tool or die holder, or the like, the metal of which shall be adapted to be adjusted 20 as to its working diameter for various sizes of work much more effectively and with more perfect accuracy than has heretofore been possible with the ordinary methods of providing for expansion and 25 contraction.

Ordinarily in order to provide for various sizes of work, it has been customary to form the tool or holder of long strips or sections adapted to be opened out lengthwise to vary the size by wedges or cones. With cutting and other kinds of tools where 30 very accurate work is to be performed, it is exceedingly difficult to obtain a perfect adjustment for the exact size required, particularly without throwing the working surface of the tool off center.

My invention avoids the difficulties incident to the ordinary methods of adjusting the size, and it consists in its essentials in 40 expanding or contracting the tool or holder in radial planes, so to speak, instead of longitudinally. To obtain this result, I form the body of the tool from a strip or bar of suitable metal formed in a spiral with 45 the spiral convolutions held together or compressed longitudinally so as to form substantially a solid body portion of the metal, and the desired accurate expansion is obtained by forcing the tool body on a conical 50 holder, so that as the body of the tool is advanced on the cone, the spiral convolutions will be expanded or contracted by increasing or decreasing the diameter of the convolutions.

55 I have illustrated my invention in the drawings with reference to a reamer and a

tap for interior or exterior thread cutting, but it will be understood, of course, that the novel construction to be hereinafter particularly pointed out and claimed can be readily 60 adapted to the formation of a great variety of tools and holders in which it is desirable to expand or contract the tool body for varying sizes of work.

In the drawings,

65 Figure 1 is a side elevation partly in section of the tool blank for an expansible reamer.

Fig. 2 is a longitudinal section of an exterior thread cutter.

70 Fig. 3 is a central longitudinal section of my invention as applied to an expansible reamer.

Fig. 4 is a perspective view of a reamer with the flutes spirally cut.

75 Fig. 5 is a perspective view of the tap embodying my invention.

Fig. 6 is a longitudinal section thereof.

In order to form the blank for an expansible reamer, for example, I take a strip 80 of metal of the proper length, rectangular in cross section, and of such size and thickness as may be suitable for the particular purpose. For example, for a reamer an inch or an inch and a half in diameter, I take 85 a strip one-eighth of an inch thick and one-half inch wide and wind it on a cylinder or mandrel into a spiral coil and bring the coils together, confining it longitudinally and then annealing to soften the metal so that 90 it will remain permanently in a closed coil, as indicated in Fig. 1, in which 1 represents the coil of metal. A conical hole 2 is then bored out of the coil of a shape to correspond to the conical surface of the shank of 95 the reamer upon which the body portion is to be mounted. The flutes are cut and the blank then retempered, whereupon it is threaded interiorly to correspond to the threads 4 cut on the cone shaped end 5 100 of the shank 6 of the tool.

In the exemplification of the invention as shown in Fig. 3, the shank of the tool is screwthreaded at 7 to receive a lock nut 8 against which the body of the reamer abuts 105 and the outer end of the shank is also provided with a screw-threaded portion 9 to hold a locking nut to abut against the outer end of the reamer body when it expands beyond the end of the cone shaped portion. 110

It is evident that with this construction, by advancing the reamer on the cone 5, a

very accurate and perfect expansion may be obtained.

With the body of the reamer constructed as outlined above, it is possible to provide an expansion reamer with spiral flutes as shown in Fig. 4, in which the spiral flutes are indicated at 10.

It will be readily seen that the construction above described is equally applicable for a tap for thread cutting as indicated in Figs. 5 and 6, in which 11 is the shank of the tap, 12 the body of the tap made up of spiral convolutions with the bore 13 cone shaped and interiorly threaded to fit the threads of the cone portion 14 of the tool. The cutting teeth 15 of the tap are given a pitch to correspond to the pitch of the spiral, or rather the pitch of the spiral from which the body of the tap is made is constructed so that cutting teeth will always be formed on the body of the metal and will not cross any spiral portion. A single tooth for each spiral convolution, or a plurality of teeth may be formed, two of such teeth being indicated in the illustration of the tap shown in Figs. 5 and 6.

For an exterior threader, the spiral 20 (Fig. 2) is cut cylindrical on the inside and conical on the outside. The outside is threaded at 21, and the inside cut with the thread forming faces 22. A sleeve 23 is provided having a conical, threaded interior terminating in a cylindrical end 24. A shank 25 is provided to fit the portion 24, and a lock nut 26 is employed to lock the sleeve in the desired position. Advancing the sleeve on the shank will compress the spiral causing the convolutions to become smaller and the spiral tool slightly longer, thereby adjusting its working diameter.

It will be evident that the tap can be expanded with great accuracy, and with my invention applied to the construction of taps, the expansion of the metal as it is ad-

vanced on the cone has the effect of bringing the cutting teeth slightly out of line or in somewhat zigzag position, which presents a much more effective cutter.

While I have not illustrated my invention in connection with other cutting tools or holders, it will be evident that the construction can be applied to a great many uses where expansion tools are desired, dies, mandrels, bearings and other uses being the constructions which readily suggest themselves. Thus the mandrels would be constructed like the reamers, except the working surface would be smooth and the bearings could be made like the exterior thread cutter.

It is not desired in this application to be construed as mentioning all variations and modifications which suggest themselves to me, since it is desired here to point out, describe and claim the essential characteristic of the tool made up of a spiral.

Having thus described my invention, what I claim as new and desire to secure by Letters Patent, is:—

1. A tool comprising a spiral of metal having working surfaces, and a holder for said metal spiral, with correspondingly screw threaded engaging surfaces between the spiral and holder, said spiral having a plurality of threads throughout its length, whereby the rotation of the metal spiral will adjust the working diameter of the tool.

2. A tool comprising a spiral of metal having working surfaces, and a holder for said metal spiral, with correspondingly screw-threaded engaging surfaces between the spiral and holder, said spiral having a plurality of threads throughout its length, whereby the rotation of the metal spiral will adjust the working diameter of the tool, and a lock nut to hold said tool in adjusted positions.

JAMES H. AUBLE.
